(57) **CLAIM**

The ornamental design for a laboratory instrument for executing molecular biology and diagnostic applications, as shown and described.

DESCRIPTION

Laboratory instrument for executing molecular biology and diagnostic applications

1.1 : Perspective

1.2 : Front

1.3 : Back

1.4 : Left

1.5 : Right

1.6 : Top

1.7 : Bottom

1.8 : Perspective

The broken lines in the figures illustrate the portions of the laboratory instrument for executing molecular biology and diagnostic applications that form no part of the claimed design.
